UNITED STATES PATENT OFFICE.

GEORGE GILL, OF TAUNTON, MASSACHUSETTS, ASSIGNOR TO REED & BARTON, OF SAME PLACE.

DESIGN FOR A TEA-SERVICE.

Specification forming part of Design No. 6,802, dated August 12, 1873; application filed June 25, 1873.

To all whom it may concern:

Be it known that I, GEORGE GILL, of Taunton, in the county of Bristol and State of Massachusetts, have invented a new and original Design for a Tea-Service; and I do hereby declare the following to be a full, clear, and exact description of the same, reference being had to the accompanying drawing, forming part of this specification, in which—

Figure 1 is a side elevation, and Fig. 2 a top view, of the cover partly broken out.

The nature of my design is fully represented in the accompanying drawing; wherein A is the body of the tea-pot, B, the cover; C, the handle; D, the spout; and E the legs. The cover B is provided with a vertically-channelled mound, b, on which sits the lion. The handle C has at the upper end a pentagonal face, on which a vessel is represented as moving under full sail, while it passes round in a curve to the body, becoming smaller and smaller as it approaches the same. It is then carried upward thereon and made to cross, terminating in a leaf and making a triangle, whose longest side rests upon the body of tea-pot. It is supported upon two diverging stems, whose leaves are spread oppositely. The spout D is four-sided upon the base or lower part, the broadest resting upon the body of tea-pot, while the narrowest is plain and opposite thereto. The two, which are clearly presented to the eye from a lateral and a per-

spective view, are concaved, and ornamented with leaves located upon their respective stems. The legs E have on the front face a channel, in which is placed three leaves, there being above this a circular indentation ornamented within, and again above this three flowers with their stems brought together at the bottom. The upper part of the legs is projected laterally, and from each of these projections is a pendent pear or other fruit. F represents the elongated flange that uprises from the seat on which the cover rests. This is flared and drawn to a point, both opposite to spout and handle.

Having thus described my invention, what I claim as new, and desire to secure by Letters Patent, is—

1. The cover ornamented as shown and described.
2. The handle C of the design shown and described.
3. The spout D of the ornamental configuration shown and described.
4. The legs shaped and ornamented substantially as shown and described.
5. The elongated flange F about the seat of cover, flared and pointed as shown and described.

GEORGE GILL.
